ORNAMENT DISPLAY SUPPORT

Arthur E. Court, 601 Ortega,
San Francisco, Calif. 94122

Filed Jan. 9, 1970, Ser. No. 20,856

Term of patent 14 years

Int. Cl. D6—01

U.S. Cl. D80—9

FIG. 1 is a perspective view of a display stand embodying my new design.

FIG. 2 is a top plan view thereof.

FIG. 3 is a front elevational view thereof.

FIG. 4 is a side elevational view thereof.
FIG. 5 is a fragmentary front elevational view of a modified form of the display stand shown in FIG. 1, the base being the same as that shown in FIGS. 1-4.

I claim:

The ornamental design for an ornamental display support, substantially as shown and described.
